UNITED STATES PATENT OFFICE.

HERMAN BRAUER AND LON H. CRON, OF GARBER, OKLAHOMA.

ROCK-BIT BREAKER.

Application filed February 6, 1926. Serial No. 86,647.

This invention relates to rock bit breakers and it is an object of the invention to provide a device of this kind adapted for use in connection with the table of a rotary drilling rig to tighten up or unscrew the bit.

Another object of the invention is to provide a device of this kind adapted to be engaged within the square of the rotary table and which is provided with means whereby the device may be readily and conveniently applied or removed with respect to the table.

The invention consists in the details of construction and in the combination and arrangement of the several parts of our improved rock bit breaker whereby certain important advantages are attained and the device rendered simpler, less expensive and otherwise more convenient and advantageous for use, as will be hereinafter more fully set forth.

The novel features of our invention will hereinafter be definitely claimed.

In order that our invention may be the better understood, we will now proceed to describe the same with reference to the accompanying drawing, wherein:—

Figure 1 is a view in perspective illustrating a breaker constructed in accordance with an embodiment of our invention positioned to be received within the square of the table of a rotary drilling rig;

Figure 2 is a view in elevation illustrating the device in applied position, the table being indicated by broken lines and a holding wrench being engaged with the drill collar;

Figure 3 is a view in top plan of the breaker as herein disclosed, an applied bit being indicated by broken lines;

Figure 4 is a view in side elevation of the device as illustrated in Figure 3.

As illustrated in the accompanying drawing, T denotes the table of a rotary drilling rig of any desired or preferred type and which is provided at its axial center with the square or opening 1.

Our improved breaker B is formed of any desired material and is of such dimensions

and configuration to be snugly received within the square or opening 1. Disposed through the breaker B at the central portion thereof is an opening 2 of a form to permit the insertion therethrough of a rock bit R and whereby the bit R is held against rotation independently of the breaker B. The ends of the opening 2 are arcuate in form to properly receive the drill bit. The upper surface of the breaker B has hingedly connected therewith at 3 the extremities of a bail 4 whereby the breaker may be readily applied to or removed from working position with respect to the table T or otherwise handled as the occasions of practice may necessitate.

When it is desired to either remove or tighten up the bit R with respect to its collar C, the bit R is positioned or received with the breaker B and the table T caused to rotate in desired direction. During the rotation of the table T, a conventional wrench D is engaged with the collar C so that the desired relative rotation of the bit R with respect to the collar C may be readily effected while the table T is in rotation.

From the foregoing description it is thought to be obvious that a rock bit breaker constructed in accordance with our invention is particularly well adapted for use by reason of the convenience and facility with which it may be assembled and operated, and it will also be obvious that our invention is susceptible of some change and modification without departing from the principles and spirit thereof and for this reason we do not wish to be understood as limiting ourselves to the precise arrangement and formation of the several parts herein shown in carrying out our invention in practice except as hereinafter claimed.

We claim:—

In a rock bit breaker a bushing consisting of a body which is square in plan and provided at its center with an elongated opening, the end walls of which are arcuately curved and the side walls of which are parallel, a bail member pivoted at its ends upon the face of the body at points upon a line disposed transversely across said open-

ing and at a point midway between the ends thereof, the intermediate portion of the bail being spaced from the end portions thereof for a distance greater than one-half of the 5 length of the opening and less than one half of the length of the side of the body whereby the bail may be swung toward either end of the opening and its intermediate portion

will lie within the sides of the body and beyond the adjacent curved end of the opening. 10

In testimony whereof we hereunto affix our signatures.

LON H. CRON.
HERMAN BRAUER.
